BILLFOLD

Arthur Rauhaus, Kittanning, Pa.

Application June 10, 1938, Serial No. 218,619

3 Claims. (CL 156—36)

The present invention relates to billfolds constructed of soft pliable leather and has for its primary object to provide an integrally formed gusseted change holding compartment adapted 5 to be collapsed into a substantially flat condition when the billfold is folded.

A further important object of the invention is to provide a billfold formed of a minimum number of flat pliable leather sections connected 10 to each other and folded in a compact form to provide a plurality of bill compartments, a gusseted change or key compartment, a plurality of card compartments and a secret bill compartment formed on one of the walls of the main bill 15 compartment, said secret bill compartment being slidably insertable in one of the card compartments to normally lie in a hidden position therein.

A further object of the invention is to provide 20 a billfold of this character in which the several sections are secured to each other by sewing and wherein the blanks forming the sections are constructed and arranged so that the amount of sewing required for securing the parts together 25 is reduced to a minimum.

An additional object is to provide a billfold of simple and practical construction which is neat and attractive in appearance, relatively inexpensive to manufacture and otherwise well 30 adapted for the purposes for which the same is intended.

Other objects and advantages reside in the details of construction as more fully hereinafter described and claimed, reference being had to the accompanying drawings forming part hereof wherein like numerals refer to like parts throughout, and in which.

Figure 1 is a plan view of the blank sections forming the invention showing the same secured 40 to each other in open position before folding.

Figure 2 is a plan view of the inner side of the billfold in completed condition and unfolded.

Figure 3 is a longitudinal sectional view taken substantially on a line 3—3 of Figure 2.

Figure 4 is a transverse sectional view taken substantially on a line 4—4 of Figure 3.

Figure 5 is a perspective view of the billfold in folded position, and

Figure 6 is a transverse sectional view taken substantially on a line 6—6 of Figure 3.

Referring now to the drawings in detail, with particular reference to Figure 1, the billfold is shown as formed from a pair of main blank sections A and B, a flap section C, and a wall section D. The blank A includes a panel 5 along one

longitudinal edge of which extends a half panel section 6 and a half panel section 7 integrally connected along one edge with the panel 5, the line 8 designating a line of fold between the main panel 5 and the half panels 6 and 7. The 5 adjacent edges of the half panels 6 and 7 are spaced apart and the half panel 7 is of greater width than the half panel 6 and provided with longitudinal fold lines to form gusseting along each longitudinal edge of the half panel 7. It 10 will be apparent that when the half panel 7 is folded along the lines 8 the free longitudinal edges of the half panels 6 and 7 terminate substantially in a common plane.

The blank B is also formed of a main panel 15 10 and a half panel 11 connected by a fold line 12, the free edges of panels 6 and 11 being connected to each other by stitching 13. The free longitudinal edge of the half panel 7 is connected to one longitudinal edge of the blank D by stitching 14, said blank D having its unsecured edge in partially overlying position with respect to the half panel 11 of the blank B.

Adjacent the connected edge of the half panels 6 and 11 is a fold line 15 which is in the plane 25 of the connected edge of the blank D. After securing the blanks together in the manner indicated the blanks A and B are folded upon each other along the fold line 15 with the half panel 7 outermost and the panels are then further 30 folded along the fold lines 8 and 12, the half panel 7 remaining outermost so that the parts will occupy the position as shown in Figure 2 of the drawings. The end edges and the free longitudinal edges are then connected by stitching 35 16, thereby forming a compartment 17 between the flatwise positioned panels 5 and 10. The panels 5 and 10 have a greater width than the half panels 6 and 11, thereby exposing a portion of the wider panels when the parts are in folded 40 position and the exposed portion of the panel 10 is provided with a longitudinally extending opening 18 which may be provided with a slide fastener 19 of conventional construction. The opening 18 thus affords access to the compartment 17 which constitutes a bill compartment. The longitudinal edges of the half panels 6 and 7 immediately adjacent the opening 18 are 45 free and provide an opening affording access to a second bill compartment 20.

The half panels 6 and 11 being folded upon each other, constitute a card compartment 21, the free edges 22 and 23 of said half panels defining an opening affording access to said compartment. The blank D constitutes one of the walls for the 55

compartment 20, a portion of said blank bridging the space between the adjacent edges of the half panels 8 and 1, as shown at 24 and the free end of the blank D is removably inserted in the card compartment 21. The under side of the inserted end of the blank D has secured thereto a piece of material 25 by stitching 26 which extends around three sides of the piece of material, the fourth side of the material being free and defining a pocket 27 which is completely contained within the card compartment 21 and constitutes a secret bill compartment.

By reason of the gusseting indicated at 28, formed by the fold lines 9 of the half panel 1, a compartment 29 is formed which is of an expandable nature and adapted to hold loose coins, keys and similar articles. The open end of the compartment 29 is adapted to be closed by a flap 30 which has one end overlapping the outer surface of the half panel 1 and secured thereto by a snap fastener 31. The flap 30 is formed from the blank C and has its other end extending inwardly of the compartment 29 and secured at the edge portion of the billfold by the stitching 16.

By reason of the relatively large area provided for the compartment 17 the same is admirably adapted for holding larger papers such as checks and the like and the compartment 20 is adapted for holding bills. The compartment 21 is suitable for holding cards, passes, tickets and similar articles and since the blank C is free within the compartment 29, except at the end portion thereof, similar articles may also be inserted between the blank C and the blank D, as will be apparent from an inspection of Figure 3 of the drawings.

The slide fastener 19 may be omitted without interfering with the pocket construction found between the panels 5 and 10. Access to the compartment 17 therebetween may then be had through the opening 18.

It will also be apparent that the billfold may be folded upon itself at a transverse medial line into a compact form as shown in Figure 5.

It is believed the details of construction and manner of use of the article will be readily understood from the foregoing without further detailed explanation.

Having thus described the invention, what I claim is—

1. A billfold comprising a plurality of pieces of flexible material including a pair of main members each embodying a panel section and a half panel section projecting from one longitudinal side edge of the panel, stitching securing said half panel sections together and a second half panel section on one of the panels having fold lines to form gussets defining the opposite side edges of a pocket when the sections are folded

upon each other in a predetermined manner, said panels and half panels when folded cooperating to form a pocket at one end of the billfold, a strip of material secured along one longitudinal edge to said last named half panel and having a free end slidably inserted in said last named pocket and a pocket carried by the inserted end of said strip. 5

2. A billfold comprising a pair of main sections of flexible material, each section including a rectangular panel and a fragmentary panel projecting laterally from one longitudinal edge of the rectangular panel, said sections having fold lines defining the respective panels, stitching connecting the longitudinal free edges of the fragmentary panels together, said rectangular panels being folded flatwise upon each other to form a compartment therebetween and said fragmentary panels being likewise folded flatwise upon each other to form a pocket, stitching securing the folded end edges of the rectangular panels and the outer end of the fragmentary panels, the inner end of said last named panels being free to provide an opening affording access to the pocket, a second fragmentary panel projecting from one of the rectangular panels and provided with parallel fold lines forming gussets, a flexible strip secured along one longitudinal edge to the free edge of said gusseted panel, said strip extending parallel to said rectangular panels and adapted to lie flatwise against one of the panels to form a compartment wall, a pocket carried at the free end of said strip and adapted for insertion in the second named pocket and a flexible strip secured to the last named fragmentary panel outwardly of the gussets and cooperating therewith to form a pocket and a flap on said last named strip for closing said last named pocket. 10 15 20 25 30 35

3. A billfold formed of a plurality of blank sections, including an L-shaped blank section and a U-shaped blank section, the latter including a pair of spaced parallel leg portions, one of said leg portions being secured to said L-shaped section to provide coextensive end panels adapted for folding flatwise upon each other to form a compartment therebetween, and a substantially rectangular wall section secured along one longitudinal edge to the free edge of the other leg portion of said U-shaped section, said wall section being positioned flatwise against one of said panels to form another compartment therebetween, said last named leg portion having gusset fold lines and a back section secured to said last named leg portion and cooperating therewith to form an expandible pocket, said back section being free at one end to provide an opening for the 40 45 50 55 pocket, and a flap on said free end of the back section for closing said opening.

ARTHUR RAUHAUS.
